CONTAINER CLOSURE

Jack W. Soffer, St. Louis, Mo., assignor to Development Research, Inc., St. Louis, Mo., a corporation of Missouri

Application August 10, 1950, Serial No. 178,605

4 Claims. (Cl. 220—27)

1

This invention relates in general to container closures and more particularly to certain new and useful improvements in container closures of the type having means for engagement with the container to form a seal, which means must be broken away to permit use of the container contents.

The primary object of the present invention is to provide a container closure which integrally incorporates a tooth member for locking engagement between upper and lower shoulders formed in the neck or discharge spout of a container to prevent unauthorized access to the contents thereof.

It is a further object of the present invention to provide a container closure having a locking tooth and means associated therewith for readily breaking same to allow removal of the closure from the container.

It is an additional object of the present invention to provide a container closure which may be utilized as a cap after the disjunction of the locking tooth and which is economically fabricated and durable in usage.

With the above and other objects in view, my invention resides in the novel features of form, construction, arrangement, and combination of parts presently described and pointed out in the claims.

In its general organization, the present invention is somewhat similar to that disclosed in my co-pending application, Serial No. 131,804, filed December 8, 1949, for Improvements in Tamper-Proof Container Closures. The structure there discloses a locking tooth substantially in the plane of the lower margin of the closure. It does not rely upon the use of a lower shoulder, nor does it provide a fulcrum to act against such lower shoulder for breaking the locking tooth from the closure, and it differs in other respects also from the present closure structure.

In the accompanying drawing—

Figure 1 is a front view of a container having engaged thereon a closure constructed in accordance with and embodying the present invention;

Figure 2 is an enlarged transverse sectional view taken along line 2—2 of Figure 1;

Figure 3 is a side view of the closure;

Figure 4 is a bottom view of the closure; and

Figure 5 is a fragmentary transverse sectional view taken along line 5—5 of Figure 3.

Referring now in more detail and by reference characters to the drawing which illustrates a preferred embodiment of the present invention,

2

A designates a container fabricated preferably of stainless steel and being of the character adapted to contain materials under gas pressure, such as fluffed cream and the like. Said container A comprises a body section 1 and a removable top 2, from which there projects upwardly and outwardly a relatively short, cylindrically formed discharge neck 3 having an axial bore 4 for receiving a separately provided valve mechanism (not shown) to permit discharge of the contents, said valve mechanism not forming a part of this invention. Approximately midway its length the neck 3 is diametrically reduced in the formation of an annular groove 5 with upper and lower shoulders 6, 6', respectively.

Provided for closure-wise disposition upon the discharge neck 3 is a closure or cap member B, fabricated preferably of a thermoplastic, such as a polyvinyl resin, and having a substantially cylindrical body section 7 which tapers slightly outwardly toward its lower end, its upper end being closed by an inclined top wall 8. Throughout its length the closure B is of greater diameter than the neck 3. Integrally formed with and projecting outwardly from the body section 7 is an ear or tab 9 having a relatively large base portion 10, the inwardly presented face of which is integral and continuous with the inner face of the body section 7. Extending upwardly in outwardly spaced relation to the body section 7 from the base portion 10 is a stem member 11 having its upper end contoured to provide a surface 12 inclined oppositely to the inclination of the top wall 8.

In elevated relation to the lower margin of the body section 7 of the closure B and protruding inwardly from the portion thereof forming the inwardly presented face of the base 10 of the ear 9 is a flange-like projection or tooth 13 having its upper surface in a plane substantially normal with the vertical axis of the closure B and having an inclined planar under face to provide a camming surface for reasons appearing more fully hereinafter. The end or central face of the tooth 13 is transversely arcuated and spaced from the diametrically opposite portion of the closure B a distance less than the diameter of the neck 3 of the container A. On its inner face the closure B is scored to provide a line or zone 14 of weakness of frangibility which defines the base 10 of the ear 9 for permitting facile disjunction of the ear 9 with the tooth 13 from the closure B by fracture therealong.

Formed on the inner surface of the closure B is a plurality of spaced upwardly tapering verti-

cal ribs 15, the inner faces of which are radially distant from the vertical axis of the closure B substantially equivalent to the radius of the discharge neck 3 for superficial abutment against the outer face thereof when the closure B is disposed thereon.

Since the distance between the end or central face of the tooth 13 and the opposite portion of the closure B is less than the diameter of the discharge neck 3, the closure B may only be 10 enclosingly disposed about the neck 3 upon the application of downwardly directed pressure upon the top wall 8 which causes a camming action to develop between the inclined underface of the tooth 13 and the upper portion of the neck 3. 15 This action results in the closure B being momentarily deformed by outward flexure along the line of weakness 14 causing the tooth 13 to be sprung outwardly allowing its end face to ride along the outer face of the neck 3. As the end 20 face of the tooth 13 loses contact with the upper portion of the neck 3 upon approaching the annular groove 5 the tooth 13 will snap inwardly for projection therein with consequent return of the closure B to its normal configuration. It 25 will thus be seen that the line of weakness 14 provides a line of flexibility as well as a line of fracture.

With the tooth 13 so engaged within the groove 5 the closure B is effectively locked upon the neck 3 in what might be called sealed condition. Withdrawal of the closure B is prevented by abutment of the upper face of the tooth 13 against the shoulder 6. Therefore, with the closure B so retentively engaged, a purchaser or would-be user is positively assured that adulteration or usage of the container contents has not occurred since shipment from the processor. In this connection it should be noted that the presence of the ear provides a visual indication that unauthorized access to the container contents has not been made.

In order to disengage the closure B from locked position, a downward and outward pressure is asserted by the user upon the inclined surface 12 of the ear 9, said surface 12 providing a convenient pressure-receiving area for the user's finger. The inclination of the top wall 8 serves to permit easy and comfortable positionment of the user's finger upon the said surface 12. This force so applied causes the inwardly presented face of the enlarged base portion 10, below the tooth 13, to rotate inward and press against the outer surface of the container discharge neck 3 below the lower shoulder 6. In this position, the enlarged base portion 10 serves as a fulcrum for the ear 9, which acts as a lever. Inward pressure causes further rotation and resultant deformation of the closure B, until its fracture is brought about, beginning in the line of weakness 14 adjacent the tooth 13 and progressing downwardly along the sides of the base 10 to the lower margin of the closure B. The user can thereby effect clean and complete removal therefrom of the ear 9 and the tooth 13. By this disjunction of the tooth 13, the closure B is freed for withdrawal from the discharge neck, whereby the valve mechanism (not shown) may be mounted for discharge of the container contents.

Subsequent to the breaking off of the tooth 13, the closure B may be utilized as a cap throughout the usage of the container A as the engagement between the vertical ribs 15 and the outer surface of the discharge neck 3 provides means

for maintaining the now tooth-less closure B relatively snugly when in closure-wise disposition.

It should be understood that changes and modifications in the form, construction, arrangement, and combination of the several parts of the container closure may be made and substituted for those herein shown and described without departing from the nature and principle of the present invention.

Having thus described my invention what I claim and desire to secure by Letters Patent is:

1. A container closure comprising a cylindrical body section open at its lower end and having a top wall, an ear integrally formed with said closure and having a base portion, the inwardly presented surface of said base portion being continuous with the inner surface of the body section, a tooth projecting inwardly from the inwardly presented surface of said base portion, a stem projecting upwardly from said base portion in outwardly spaced relation to the body section, the said base portion, tooth, and tab being heavily constructed to form a lever bearing at said base portion fulcrum-wise inward against the container at a point below said tooth, and a thinned frangible area in said body section demarking said lever and adapted for facile fracturing outward of the upper edge of said tooth.
  2. A container closure comprising a cylindrical body section open at its lower end and having an inclined top wall, an ear integrally formed with said closure and having a base portion, the inwardly presented surface of said base portion being continuous with the inner surface of the body section, a tooth projecting inwardly from the inwardly presented surface of said base portion, a stem projecting upwardly from said base portion in outwardly spaced relation to the body section, said stem being provided at its upper end with an inclined surface adapted for receiving pressure applied thereon, the inclination of said surface being opposite to that of the top wall, the said base portion, tooth, and tab being heavily constructed to form a lever bearing at said base portion fulcrum-wise inward against the container at a point below said tooth, and a thinned frangible area in said body section demarking said lever and adapted for facile fracturing outward of the upper edge of said tooth.
  3. A closure container having a substantially cylindrical body section open at its lower end and having a top wall, an ear projecting outwardly from the body section and integrally formed therewith, said ear having a base portion the inwardly presented face of which is continuous with the inner surface of the body section, said body section being scored to define the inwardly presented face of the base portion of the ear by a line of weakness, a tooth projecting inwardly from the inner face of said base portion in upwardly spaced relation to the bottom margin of said body section, a stem projecting upwardly and outwardly from the base portion, said stem having formed at its upper end an inclined surface for receiving pressure reacted fulcrum-wise by inward pressure of said base portion against the container at a point below said tooth to cause outward and downward movement of the ear to effect fracture along the line of weakness and result in removal of the ear and tooth from the closure.

4. Form a container having a cylindrical neck whose outer surface is annularly recessed in the formation of upper and lower shoulders, a clo-

sure molded of frangible material having a top wall and a substantially cylindrical body adapted to enclose both the upper and the lower shoulders of such container neck, a tab molded integrally therewith having an enlarged base portion adapted to bear against such lower shoulder in fulcrum-wise engagement, the said tab further having an outstanding stem adapted to receive finger pressure downward thereon, and further having a tooth portion projecting inwardly 10 from said cylindrical body at a point spacedly above the lower margin of said enlarged base portion, and a thinned area in said cylindrical body circumscribing the said base and tooth of said tab, the said closure being so constructed and 15 arranged that the bending moment arising from

such finger pressure on said stem and the fulcrum-wise engagement of said base against the lower shoulder of such container neck serves to fracture the thinned area commencing above said tooth and progressing downwardly to effect removal of the entire tab from said closure.
